HEATING UNIT

Filed Jan. 7, 1928

FIG. 1.

FIG. 3.

WITNESS:

Bob P. Mitchell.

INVENTOR
Frank J. Werner, Jr.
BY
Augustus B. S. Foughton
ATTORNEY.

UNITED STATES PATENT OFFICE

FRANK J. WERNER, JR., OF LANDSDALE, PENNSYLVANIA

HEATING UNIT

Application filed January 7, 1928. Serial No. 245,195.

The principal objects of the present invention are to provide a satisfactory and efficient circulation of water; to insure an efficient exposure of the heating surface of the unit to the fire; to obviate objectionable accumulations of dirt and of dust on the outside of the unit; to provide against clogging of the water ways; and to afford an extended heating surface.

10 Other objects of the invention will appear from the following description at the end of which the invention will be claimed but it may be said that, generally stated, a water heating unit of the invention comprises a hollow annular body of flattened elliptical form in cross section and corrugated on the outside and having closely spaced water inlet and outlet connections and including a partition or baffle disposed in the plane of the body and arranged between the inlet and outlet connections to provide water ways and ported opposite said connections to afford communication between said water ways.

25 The invention also comprises the improvements to be presently described and finally claimed.

Reference will be made to the accompanying drawing forming part hereof and in which

30 Figure 1 is a top or plan view taken in section on the line 1—1 of Fig. 2.

Fig. 2 is an edge view showing the water inlet and outlet connections, and

35 Fig. 3 is a sectional view taken on the line 3—3 of Fig. 2.

There is a hollow annular body 1 of flattened elliptical form in cross section, Fig. 3. This provides a surface 2, generally inclined to the horizontal and from which dust by readily falling is not permitted to accumulate. The body 1 on the outside or periphery is corrugated to provide an extended heating surface. The water inlet and outlet connections 3 and 4 are closely spaced. 5 is a partition or baffle plate disposed in the plane of the body and arranged between the inlet and outlet connections 3 and 4 to provide unobstructed water ways 6 and 7, and this partition or baffle plate is ported opposite the connections

3 and 4, as indicated at 8, to afford communication between the water ways 6 and 7.

In practice the water heating unit may consist of a casting and it is arranged horizontally. Evidently the water ways are unobstructed to afford recirculation of water which opposes clogging. Pipes are inserted into the connections 3 and 4 and the unit is supported thereby over a fuel bed.

I claim:

A water heating unit comprising a hollow annular body of flattened elliptical form in cross section and having an opening therethrough whose axis coincides with the minor axis of the ellipse and corrugated on the outside and having closely spaced water inlet and outlet connections whose axes are arranged parallel to the radius of the annulus and including a baffle plate disposed in the plane of the body and arranged between the inlet and outlet connections to provide water ways and ported opposite said connections to afford communication between the water ways.
